Inventor
Galusha L. Samson,

By *O'Neill and Son*

Attorney

UNITED STATES PATENT OFFICE.

GALUSHA L. SAMSON, OF HONOLULU, TERRITORY OF HAWAII.

LOOSE-LEAF BINDER.

Application filed April 11, 1923. Serial No. 631,393.

To all whom it may concern:

Be it known that I, GALUSHA L. SAMSON, a citizen of the United States, and resident of Honolulu, Territory of Hawaii, have invented certain new and useful Improvements in Loose-Leaf Binders; and I do hereby declare the following to be a full, clear, and exact description of the invention, such as will enable others skilled in the art to which it appertains to make and use the same.

This invention relates to loose-leaf binders, and more particularly to binders of that class provided with clamping members equipped with flexible connections, the primary object of this invention being the provision of a simple and durable means for varying the capacity of the binder, as will hereinafter appear.

20 A further object of the invention is the production of a binder such as described, which will be efficient in operation, and present a neat and attractive appearance.

Other objects of the invention will be 25 made apparent in the following specification, and the drawings forming a part thereof.

The invention is illustrated in the accompanying drawings, which show the preferred 30 embodiment.

In said drawings,

Fig. 1 is a plan view of the binder equipped with my invention.

Fig. 2 is an enlarged fragmentary end 35 view of the binder, with the end housing removed to show the connector mechanism.

Fig. 3 is a longitudinal section taken on line 3—3 of Fig. 1, with the leaves removed.

Fig. 4 is an enlarged detail of the closed 40 end of the binder, showing the chains in dotted lines and the ratchet mechanism for operating the latter.

Fig. 5 is an enlarged sectional detail, showing means for operating the chains.

Fig. 6 is a plan view of the operating 45 chains,

Fig. 7 is a section taken through line 7—7 of Fig. 6, and,

Fig. 8 is an enlarged detail of the chain 50 pintle.

Now referring specifically to the drawing, A and A' represent the clamping members of a loose leaf binder, such as a current ledger or transfer binder, B represents the 55 loose leaves to be clamped between the mem-

bers A and A', and C and C' are the outside covers for said leaves.

In the embodiment illustrated D—D represent the flexible binding posts which extend throughout apertures provided in the leaves B, and which bind said leaves together, each of said binding posts being herein-after called a chain.

In the herein illustrated construction, each of the clamping members A and A' are of 65 hollow or tubular formation, composed of rigid material, such as sheet metal. The covers C and C' may be of stiff boards, such as are usually used for ledger covers, and are hingedly connected at 1 to the members 70 A and A'.

As before stated, the chains D are extended through apertures in the leaves, and are then wound up to draw the clamping member A down toward the member A', and 75 tightly upon the rear end of said leaves, for the purpose of holding them immovably in position.

The chains are mounted on a roller 2, being secured thereto by means of a rivet or bolt, which extends through a flattened extension 3 of the end link of the chain, and into the roller 2, as clearly indicated in Figure 3. The other end of the chain extends downwardly, in the view shown in Fig. 3, and is provided with flared 85 ends 4, extending through an aperture formed in the upper wall of the member A', where said ends are riveted or otherwise secured to the said wall. The roller 2 is suitably mounted, at each end, for rotation in the 90 member A', and is provided with a squared end 5, projecting from the body thereof, a circular socket 6, surrounding the end 5, permitting the insertion of a key 7, into the socket and around the end 5, whereby the 95 roller 2 may be rotated, as will be understood.

The chains D are tensioned by the key as described, and are prevented from becoming relaxed by means of a ball ratchet mechanism. The end 8 of the roller 2 is circular, and is provided with ratchet teeth, as shown in Fig. 4. A ring 10 surrounds the end 8, and a ball 11, controlled by spring 12 and held in slot 12, is normally pressed in position to engage the ratchet teeth and prevent rotation of said shaft to the left, while rotation to the right, to wind up the chain D, is freely permitted. For the purpose of permitting the roller to turn to the left, I provide 110

22
 a finger 13, secured to the end 5, and extending into a narrow slot formed in the end 8. The end of the finger 13 normally contacts the ball 11, and, when the roller is rotated 5 to the left by the key 7, the finger 13 will push the ball 11 backwardly against the spring 12, so as to clear the ratchet teeth and permit such rotation, as will be clearly understood. Immediately upon the release 10 of the pressure to the left upon the key 7, the ball 11 is freed and returns to its normal position.

As shown in Figs. 6 and 7, the chains D are composed of interfitting links 14, provided with longitudinally channelled front extensions 15, and, at the rear end with separated, similarly channelled rear extensions 16. The extensions on the front and rear of the links 14 are adapted for complementary interfitting engagement with the extensions on the succeeding links, as will be understood, and a pintle 17 is adapted to extend through the channels formed in the extensions, and connects the links each to 25 each, as will be understood. Each pintle 17 is composed of a body of strong metal having inherent resiliency. It is provided with a flanged head 18, and the body is split longitudinally through the head and to a point 30 just short of the rear end 19, as shown in Figs. 7 and 8. The upper portion of the body is cut away, and tapers upwardly from the rear end 19, to form a spring member 20, and a shoulder 19' and, in the forward portion 35 of said member is a socket 21 adapted to receive a stud or pin 22, extending into the channel formed in the rear extension 16 of the chain links. For the purpose of adding or removing leaves, it is obvious that 40 the chains may be separated by pressing the top portion of the head 18 of the pintle, to flex the spring member 20 sufficiently to permit the socket 21 to clear the pin 22. The pintle 17 is then pulled outwardly until the 45 shoulder 19' contacts the pin 22, at which time, however, the extensions 15 and 16 have become disconnected, as will be understood. The contact between the shoulders 19' and the pin 22 retains the pintle in position so 50 that, when the necessary leaves have been added or removed, it may simply be pushed inwardly to reconnect the links, and the pin 22 and the socket 21 snap into interfitting and interlocking engagement. A suitable 55 implement may be provided for connection to the head 18, to depress the spring portion 20.

In order to impart a finished appearance to the book equipped with my invention, I 60 provide a band 23 of flexible leather or the like. As before stated, the clamping member A is preferably formed of sheet metal. In this embodiment of the invention I have 65 here shown the top portion 24 of said member bent downwardly and inwardly and

provided with a flange 25 immediately above the bottom 26 of the member A. The top end of the band 23 is inserted between the flange 24 and the bottom 25, and secured in position by means of rivets or bolts. In the 70 lower clamping member A' is mounted a roller 27, on which is secured the other end of the band 23, an elongated slot 28 being provided in the rear end of the member A', in which the band 23 may slide during the 75 winding and unwinding operations.

It is manifest that the length of the exposed portion of the band 23 will increase or decrease as the leaves B are added or removed. The roller 27 is provided with a 80 ratchet mechanism similar to that described in connection with the roller 2, the key 7 preferably fitting the stem 5 of both rollers, the difference being that the roller 27 is free- 85 ly windable to the left instead of to the right, as in the case of the roller 2.

It is believed that the operation of the binder will be clearly understood without any further detailed description thereof. I have produced in the chain D a flexible binding post which may be disconnected for the 90 addition or abstraction of leaves, at practically any point in its length, an advantage which will be clearly apparent.

I have also provided means for quickly 95 and easily operating the permanent members and for properly adjusting the backing band 23, as will be manifest.

Various modifications of this invention 100 may be suggested to those skilled in the art. but the invention covers all such modifications as are comprehended in the appended claims.

I claim—

1. A loose leaf binder provided with two 105 tubular members adapted to clamp the leaves therebetween, a substantially flat chain, provided with detachable links, wound upon a roller in one member and extending through the leaves and rigidly se- 110 cured to the other member, and means for rotating said roller to clamp or release said leaves, substantially as described.

2. A loose leaf binder provided with upper and lower members provided with flat 115 faces adapted to clamp the leaves therebetween, a substantially flat chain composed of detachable links, wound upon a roller in one member and extending through said leaves and secured to the other member, in 120 combination with a flexible cover strip mounted on a roller in the other member, and extending through a slot therein and secured to the flat clamping face of said first-named member, and means for rotating said rollers to vary the length of the chain and of said strip.

3. A loose leaf binder provided with upper and lower tubular metallic members 125 provided with flat faces adapted to clamp 130

- the leaves therebetween, a substantially flat chain composed of detachable links, wound upon a roller in one member, and extending through the leaves and secured to the 5 clamping face of the other member, in combination with a flexible end-cover strip mounted on a roller in the other member and extending through an elongated slot therein and clamped between a flange and 10 the said clamping face of the first-named member, and means for rotating said rollers to vary the length of the said chain and said strip.
4. A loose leaf binder provided with two 15 members provided with flat faces adapted to clamp the leaves therebetween, and with a flexible binding post, in combination with a flexible end cover strip mounted on a roller in one member and extending through 20 an elongated slot therein and secured to the flat clamping face of the other member, substantially as described.
5. A loose leaf binder provided with two 25 members having opposed flat faces adapted to clamp the leaves therebetween, a flexible binding post mounted on a roller in one member and secured to the flat face of the other member, an elongated slot in the other member, adjacent and extending longitudinally of the clamping face thereof, a roller carried by said other member, and a flexible end-cover strip mounted upon said 30 roller and extending through said slot and secured to the flat clamping face of the said 35 first-named member, substantially as described.
6. A loose leaf binder comprising two 40 clamping members, one of which carries a roller, a flexible, substantially flat chain adapted to extend through the leaves to be 45 bound, and rigidly secured at one end to 50 one of the clamping members, and connect- ed at the other end to said roller, said chain being formed of complementary links connected by pintles, means releasably preventing longitudinal movement of the pintles relative to the links, and cooperative means carried by the links and pintles preventing separation of the latter from the links, substantially as described. 55
7. A loose leaf binder comprising two tubular clamping members, each provided with a roller, a flexible chain wound upon the roller on one member and extending through an aperture in the clamping face 60 thereof and through the leaves to be bound, and rigidly secured to the clamping face of the other member, and a flexible cover strip mounted on the roller of the other clamping member and extending through 65 a slot therein and parallel to the said chain, and rigidly connected to the other clamping member substantially as described.
8. A loose-leaf binder comprising two 70 tubular clamping members, each provided with a roller, a flexible chain wound around the roller on one member and extending through an aperture in the clamping face thereof, and through the leaves to be bound, and rigidly secured to the clamping face of 75 the other member, a flexible cover strip mounted on the roller of the other member and extending through a slot therein and parallel to the said chain and rigidly connected to the clamping face of the other member, and means connected to each roller whereby it may be freely rotated in one direction, but prevented from rotation in an opposite direction, substantially as described. 80

In testimony whereof I affix my signature.

GALUSHA L. SAMSON.
